TELEVISION STANDS

William Remstein, Syracuse, N. Y., assignor to
I. J. Elman, Syracuse, N. Y.

Application February 12, 1954, Serial No. 409,839

4 Claims. (Cl. 248—163)

This invention relates to wrought iron stands, and more particularly to a rigid, economical stand for supporting television receivers and the like.

Stands for supporting the so-called table model television receivers are required to be rugged, economical, while at the same time exhibit a degree of aesthetic appeal. In order that a given stand may be adapted for different size television receivers, adjustment of the size of the supporting bed is desirable.

The present invention is directed to a wrought iron stand composed of essentially two pairs of like parts formed from round wrought iron stock, the structure requiring a minimum number of welds when assembled, and the arrangement being such that the parts, when assembled, interlock with one another to produce a stand of unusual rigidity and desirable appearance, at a minimum of expense.

The above and other novel features of the invention will appear more fully hereinafter from the following detailed description when taken in conjunction with the accompanying drawings. It is expressly understood that the drawings are employed for purposes of illustration only and are not designed as a definition of the limits of the invention, reference being had for this purpose to the appended claims.

In the drawings, wherein like reference characters indicate like parts:

Figure 1 is a perspective view of a stand embodying the invention;

Figure 2 is a fragmentary sectional view taken on the plane 2—2 of Figure 1; and

Figure 3 is a fragmentary sectional view taken on the plane 3—3 of Figure 1.

Referring to Figure 1, there will be seen a stand composed of a pair of like bars 8 and 10, having center horizontal sections 12 and 14 and leg portions 16 and 18, and 20 and 22. For pleasing appearance, the leg portions join the horizontal sections by curved sections as at 24. The bars 8 and 10 are substantially identical, and in general, will extend from front to rear in the completed stand. The bars 10 and 12 are tied together by longitudinally extending bars 26 and 28 which have horizontal center sections 30 and 32, and leg portions 34 and 36, and 38 and 40, such leg portions being joined to the horizontal portions by curved sections as at 42, similar in all respects to the curved sections 24. Each of the bars 26 and 28 may be all in one piece, or each may be divided as shown in Figure 3, to provide two ends 41 and 43, which are adapted to project into sleeves 44 and 46. Each of such sleeves may be secured to one of the ends 41 as by welding, at 48, while the other end of the sleeve may make a close but adjustable fit over the other end 43. The sleeve may be slit as at 45, and a taper threaded sleeve 47 employed to rigidly secure the parts together.

Each of the horizontal sections 12 and 14 of the transverse bars 8 and 10 may be given offsets as at 50 and 52, such offsets being one-half the diameter of the bar, the

2

central section of the bar lying between the offsets and being thereby raised by one-half the bar diameter.

Each of the horizontal sections 30 and 32 of the bars 26 and 28 are provided with offsets as at 54 and 56, whereby the central sections of such bars between the offsets are lowered by one-half the diameter of the bars. The offsets of the bars 8 and 10, and the bars 26 and 28, are nested as indicated in Figures 1 and 2, and the legs of each corner are brought together to form a symmetrical structure with respect to a vertical plane extending at a 45° angle to the rectangular bed formed by the bars.

Such bars are preferably welded together at the offsets where such bars contact one another. For example, welds may be provided between the crossing bars, in the manner indicated at 53. The lower ends of the adjacent leg forming portions such as 16 and 36, 20 and 34, 22 and 38, and 18 and 40, may be held together by plastic or rubber-like twin socket feet 60, and may additionally be welded as at 62.

It will be seen that if the bars 28 and 26 are one piece, such bars in conjunction with bars 8 and 10 together form a rigid structure. The parts, being welded at the offsets, and having adjacent leg bars secured together at their converging ends provide a rigid structure, each part of which mutually assists the other parts in resisting torsional and bending loads. The structure is equally rigid when provided with adjustment sleeves 44 and 46, since by the clamping of the sleeve 47, such bars are given the same torsional rigidity as the solid bars.

Where adjustment sleeves are employed, as in Figure 1, the thickness of the sleeve wall and thimble wall is less than the diameter of the bar stock employed, so that a receiver lying on the central sections of bars 12 and 14 will be free and clear of the sleeves 44 and 46. In practice, such receivers have cleats or rubber feet, which may be interlocked within or without the four corners of the frame bed.

In practice, it may be desirable to dispense with the offsets and adjustment sleeves, in which case the leg portions 34, 38, 36, and 40 of the bars 26 and 28 would be cut shorter than the leg portions 16, 18, 20, and 22, by an amount equal to the diameter of the bar stock, it being understood that the offsets provide symmetrical legs, as well as a nesting action of benefit and assistance in assembly.

It will be seen from the foregoing that by a simple bending operation of four bars, and four welds at the points of contact, and the use of rubber feet and/or welds to tie the lower adjacent leg ends forming each foot together, a stand of exceptional strength and appearance results. It will appear that while iron bar of $\frac{1}{2}$ " diameter is suitable, the stand could be constructed of tubular material such as aluminum, and that rivets or screws for example as indicated at 55, where a screw is threaded in the lower member, instead of welds, could be employed to assemble and secure the parts.

While a single embodiment of the invention has been illustrated and described, it is to be understood that the invention is not limited thereto. As various changes in the construction and arrangement may be made without departing from the spirit of the invention, as will be apparent to those skilled in the art, reference will be had to the appended claims for a definition of the limits of the invention.

What is claimed is:

1. A stand for television receivers and the like, comprising four rigid bars, each having a generally straight central portion and end leg portions, extending substantially perpendicular to the central portion, one pair of said bars having their central portions extending parallel, and the other pair of bars having their central portions extending parallel, and extending over and at right

angles to the central portions of said first pair of bars, said central portions of said bars defining a rectangular support with two raised parallel rails, the leg portion of each bar lying in a common plane, the adjacent leg portion of one bar converging with the leg portion of the adjacent bar at each corner, and the converging portions being secured together at their lower ends, said horizontal portions of said bars being welded together at their four points of contact and intersection, said horizontal portions of said bars each having two offsets equal to one-half the bar diameter, the offsets of one pair of bars being up to one-half the diameter of the bars, and while the offsets of the other pair are down one-half the bar diameter, said offsets of the bars having a nesting relation immediately at the points of contact between the bars at their intersection contacts.

2. A stand for television receivers and the like, comprising four rigid bars, each having a generally straight central portion and end leg portions, extending substantially perpendicular to the central portion, one pair of said bars having their central portions extending parallel, and the other pair of bars having their central portions extending parallel, and extending over and at right angles to the central portions of said first pair of bars, said central portions of said bars defining a rectangular support with two raised parallel rails, the leg portion of each bar lying in a common plane, the adjacent leg portion of one bar converging with the leg portion of the adjacent bar at each corner, and the converging portions being secured together at their lower ends, said horizontal portions of said bars being welded together at their four points of contact and intersection, said horizontal portions of said bars each having two offsets equal to one-half the bar diameter, the offsets of one pair of bars being up one-half the diameter of the bars, and while the offsets of the other pair are down one-half the bar diameter, said offsets of the bars having a nesting relation immediately at the points of contact between the bars at their intersection contacts, said other pair of bars being parted near the middle thereof, and being provided with a coupling sleeve, the wall thickness of which does not exceed the diameter of the bars extending transversely across the stand.

3. A stand for television receivers and the like, comprising four rigid bars, each having a generally straight central portion, and end leg portions extending substantially perpendicular to the central portion, the leg portions of one pair of said bars being shorter by the vertical thickness of said central portion than the legs of the other pair of said bars, the bars of one pair being

arranged with the central portions parallel, and the bars of the other pair being arranged with the central portions parallel and at right angles to the central portions of said one pair, said central portions of the pair having the longer legs extending over the central portions of the other pair, said central portions all together forming a rectangular frame and a horizontal pattern having symmetry with respect to the longitudinal and transverse horizontal axes, said legs of the two adjacent bars at each corner extending downwardly and converging at their lower ends to form a two-bar V-leg, means for rigidly securing the central portions of said bars of one pair to the central portions of the bars of the other pair where they cross, and means for securing said adjacent bars at their ends together at the lower end of each leg.

4. A stand for television receivers and the like, comprising four rigid bars, each having a generally straight central portion, and end leg portions extending substantially perpendicular to the central portion, the leg portions of one pair of said bars being shorter by the vertical thickness of said central portion than the legs of the other pair of said bars, the bars of one pair being arranged with the central portions parallel, and the bars of the other pair being arranged with the central portions parallel and at right angles to the central portions of said one pair, said central portions of the pair having the longer legs extending over the central portions of the other pair, said central portions all together forming a rectangular frame and a horizontal pattern having symmetry with respect to the longitudinal and transverse horizontal axes, said legs of the two adjacent bars at each corner extending downwardly and converging at their lower ends to form a two-bar V-leg, means for rigidly securing the central portions of said bars of one pair to the central portions of the bars of the other pair where they cross, and means comprising a rubber cap having a figure 8 socket for securing said adjacent bars at their ends together at the lower end of each leg.
